ABSTRACT

A high voltage electron discharge device, such as the horizontal output tube for a color television receiver, has a getter assembly electrically and mechanically connected to the anode whereby the getter is maintained at anode potential.

METHOD AND STRUCTURE FOR ELIMINATING CORONA DISCHARGE IN HIGH VOLTAGE ELECTRON DISCHARGE DEVICES

BACKGROUND OF THE INVENTION

This invention relates to high voltage electron discharge devices and more particularly to a method and structure for eliminating corona discharges therefrom. These types of high voltage devices are generally characterized by a "top cap," i.e., the anode connection, instead of being located in the stem or base of the device with the remaining leads, emerges from the top of the device envelope where it is sealed in the glass thereof and connected to a cylindrical metal cap. Electrical connection to a desired circuit is made by fitting a connector to this cap. Previously, this type of device utilized a side mounted getter, below the top mica. This resulted in the flashed getter material being deposited on the sides of the bulb envelope in the area of the anode, and acted as a mirror, preventing heat radiation from the device. The loss in heat radiating capability of the device led to excessive anode heating with consequent loss of reliability, especially when the device was operated at or near its maximum design ratings.

In an attempt to solve this problem it was suggested that a top flashed getter be employed; i.e., one which flashed into the dome of the device. This type of getter was connected generally to one of the beam plates of the tube. While solving the heat radiating problem, it was found that a new problem was introduced. When such devices were run with an anode voltage as low as 5,000 V. a visible corona discharge developed at the outer edges of the top cap. This corona discharge severely damaged the glass about the seal with the result that the device eventually became defective.

OBJECTS AND SUMMARY OF THE INVENTION

It is therefore, an object of the invention to obviate the disadvantages of the prior art.

It is another object of the invention to enhance the operation of high voltage electron discharge devices utilizing a top cap.

It is another specific object of the invention to provide such a device that eliminates problems caused by corona discharges without upsetting the necessary heat radiating characteristics of the device.

These objects are accomplished in one aspect of the invention by the provision of device of the type described above wherein the getter is mounted above the top mica, near the dome of the envelope, and is maintained at anode potential.

BRIEF DESCRIPTION OF THE DRAWINGS

FIG. 1 is a partial, sectional view of an electron discharge device embodying one form of the invention; and

FIG. 2 is an elevational view of an alternate form of support for use with the invention.

DESCRIPTION OF THE PREFERRED EMBODIMENTS

For a better understanding of the present invention, together with other and further objects, advantages and

capabilities thereof, reference is made to the following disclosure and appended claims in connection with the above-described drawings.

Referring now to the invention with greater particularity, there is shown in FIG. 1 an electron discharge device 10, such as can be used as the horizontal output tube of a color television receiver. Device 10 has an evacuated envelope 12, generally of glass, and contains an electrode cage 14 which includes at least an anode 16, a cathode 18 and a getter assembly 20. Device 10 is a type of high voltage tube utilizing a top cap 22 for the anode connection. An anode lead 24 is sealed into the upper dome of the envelope 12 and is electrically connected at one of its ends to the top cap 22. The other end of the lead 24 is connected to the anode as will be described hereinafter.

The electrodes of the cage 14 are held in spaced relationship by upper and lower micas as is conventional in the art. In this particular instance only upper mica 26 is shown. The micas are held in place by various tabs or ears such as tabs 28 of anode 16 which are twisted or otherwise deformed after being inserted through the micas to maintain the micas in the proper location.

The getter assembly 20 comprises a supporting bracket 30 which is substantially semi-circular in configuration and whose ends 32 and 34 are electrically and mechanically connected to tabs 28 of anode 16. The upper portion of the support 30 has affixed thereto an upstanding electrically conductive member 36 which is connected to anode lead 24. Also affixed to support 30 is at least one getter flat 38; however, two are shown in the drawing.

A tube made as described above obviates the disadvantages of the prior art. By eliminating the getter flash from the side wall of the envelope, heat radiation is increased, and by maintaining the getter at anode potential deleterious corona discharge is eliminated.

In FIG. 2 is shown an alternate form of getter support bracket 40. Herein, the support is substantially U-shaped but having a flattened bight 42. The radius 44 joining the leg portions 46 with the bight 42 should be as large as reasonably possible to further reduce any possibility of corona discharge. Such a design can be utilized in smaller tube sizes where the space between the dome and the top mica does not allow the bracket 30 to be employed.

While there have been shown and described what are at present considered the preferred embodiments of the invention, it will be obvious to those skilled in the art that various changes and modifications may be made therein without departing from the scope of the invention as defined by the appended claim.

55 What is claimed is:

1. A high voltage electron discharge device incorporating means for eliminating corona discharge having an evacuated envelope containing an electrode cage comprised of at least an anode, a cathode and a getter assembly, said anode and cathode being positioned between a pair of insulating micas with said micas maintaining a force fit within said envelope, said anode having at least two projecting tabs extending upwardly through one of said micas; said getter assembly providing said means for eliminating said corona discharge and comprising a generally U-shaped bracket electrically and mechanically connected to said pair of

tabs on said anode and having at least one getter attached to said bracket and formed to flash upwardly; an electrical anode lead being sealed in the upper end of said device opposite the leads for said cathode; and means attached to said bracket for making electrical

and mechanical connection to said anode lead whereby, when flashed, the gettering material shall be deposited upon the inner upper surface of said envelope surrounding said anode lead.
